Application June 24, 1957, Serial No. 46,708

Term of patent 14 years

(Cl. D54—16)

FIG. 1

FIG. 2

FIG. 3

FIG. 4

Figure 1 is a side elevational view of a spud wrench showing my new design;

Figure 2 is a view taken from the right of Figure 1;

Figure 3 is a view taken from the left of Figure 1; and

Figure 4 is a section on the line 4—4 of Figure 2.

The side of my spud wrench opposite to that shown in Figure 1 is substantially the same.

I claim:

The ornamental design for a spud wrench, as shown and described.
